UNITED STATES PATENT OFFICE.

GARY B. SMITH, OF CHICAGO, ILLINOIS.

MACHINE FOR MAKING CROSS-TIE LINKS.

1,116,506.

Specification of Letters Patent.

Patented Nov. 10, 1914.

Application filed March 18, 1913. Serial No. 755,100.

To all whom it may concern:

Be it known that I, GARY B. SMITH, a citizen of the United States, residing at Chicago, in the county of Cook and State of Illinois, have invented a new and useful Machine for Making Cross-Tie Links, of which the following is a specification.

The device forming the subject-matter of this application is a machine adapted to be employed for the making of cross ties of the sort commonly used in the manufacture of spring beds, although, obviously the machine may be put to other uses.

One object of the present invention is to provide novel means for putting the initial bend into a length of wire.

Another object of the invention is to provide novel means for cutting the section of wire into a predetermined length, and for turning both the bend and the ends of the severed section to form hooks at the ends of the cross tie.

Another object of the invention is to provide novel means for feeding the length of wire intermittently for shaping.

The invention aims to provide novel means for removing the finished product from the machine.

It is within the scope of the invention to provide novel driving mechanism whereby the several portions of the structure may be actuated.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 shows the invention in side elevation; Fig. 2 is a top plan; Fig. 3 is a longitudinal section on the line 3—3 of Fig. 2; Fig. 4 is an elevation showing the opposite side of the structure from that depicted in Fig. 1; Fig. 5 is a transverse section on the line 5—5 of Fig. 2; Fig. 6 is a transverse section on the line 6—6 of Fig. 2; Fig. 7 is a horizontal section on the line 7—7 of Fig. 6; Fig. 8 is a horizontal section on the line 8—8 of Fig. 6; Fig. 9 is a sectional side elevation on the line 9—9 of Fig. 7; Fig. 10 is a section on

the line 10—10 of Fig. 8; Fig. 11 is a plan showing a slight modification; Fig. 12 is an end view of the structure shown in Fig. 11; Figs. 13, 14 and 15 are detail views illustrating different steps in the manufacture of the product as wrought by the machine herein disclosed; Fig. 16 is a perspective of the finished product; Fig. 17 is a perspective showing the manner in which the ties are deposited on the fabric chain; and Fig. 18 is a cross section on the line 18—18 of Fig. 11.

In order to locate relative positions of the parts of the device, that end thereof to which the reference character A is applied, will be considered the forward end, that end to which the reference character B is applied being considered the rear end, descriptive terms being selected accordingly.

In carrying out the invention there is provided a supporting structure, comprising a base 1 and a superposed cap 2. The base 1 adjacent the forward end of the supporting structure is provided with longitudinally extended guides 3 and at the forward ends of which are located standards 4 supporting a shaft 5 upon which is mounted to swing in a vertical plane, a trip 6. A spring 7, shown in Fig. 2, is connected with one of the standards 4 and with the trip 6, the spring 7 serving to swing the trip 6 forwardly and downwardly, into engagement with a shaft 8 which is journaled in the standards 4. Projecting forwardly from the shaft 8 is a guide 9. At one end, the shaft 8 is equipped with a crank arm 10, pivotally connected with an actuating member 11 which may be a slide, the actuating member being held in place upon the base 1 for longitudinal movement by the means of a guide 12 and by means of a screw 14, the screw 14 entering the base 1 and being slidably received in an elongated slot 15 in the actuating member 11.

Mounted to reciprocate between the guides 3 is a cross head 16 to which is secured a cap 17, shown most clearly in Fig. 3. At its ends, the cap 17 is equipped with upstanding ears 18 having aligned openings 19.

An angular grip 20 is pivotally supported upon the cross head 16 as indicated at 20^a. The grip 20 comprises a forwardly extended shank 21 and a depending jaw 22, the lower end of which may be serrated. The lower end of the jaw 22 lies between the ears 18. Nuts 23 are threaded upon the shank 21 of the grip 20.

The wire to be fashioned into cross ties is denoted by the numeral 24. The wire 24 extends through the openings 19 in the ears 18 which are connected with the cross head. 5 When the actuating member 11 is thrust rearwardly, the crank arm 10 will be actuated, rotating the shaft 8 and causing a depression of the free, forward end of the guide 9. The upper end of the trip 6 is then 10 exposed, and rests upon the shaft 8. Suppose that the cross head 16 is thrust forwardly. Then the nuts 23 on the shank 21 of the grip 20 will ride along, engage and tilt the trip 6 and thus force the lower end 15 of the jaw 22 into engagement with the wire 24, the wire 24 being bound against the cap 17. If now the cross head 16 be moved rearwardly, the wire 24 will be moved rearwardly, the trip tilting to permit nuts 23 to move free from the end of the trip. So 20 long as the cross-head 16 is moving rearwardly, and so long as the wire 24 is under tension, the lower end of the jaw 22 will be maintained in binding relation to the wire. 25 But, however, when the rearward movement of the cross head 16 ceases, the jaw 22 will no longer engage the wire 24 and the cross head 16 may move forwardly without carrying the wire 24 with it. In this manner, the 30 wire 24 will be moved rearwardly with a step-by-step movement.

At times it may be desirable to permit the cross head 16 to reciprocate freely without moving the wire 24 rearwardly. Under 35 such circumstances, the guide 9 is raised through the medium of the actuating member 11, the crank arm 10 and the shaft 8 until the upper edge of the guide 9 is in substantial alinement with the upper, forward end of the trip 6. Then, the nuts 23 will not engage with the forward end of the trip 6, and since the trip 6 will not be rocked in a rearward direction, the shank 21 of the grip 20 will not be elevated, and the 40 jaw 22 will not be forced downwardly into engagement with the wire 24.

Passing now to a description of the means whereby a reciprocatory movement is imparted to the cross head 16, it will be noted 45 that the cross head is provided with a screw bolt 25 upon which is pivoted the forward end of a link 26, the rear end of which is pivoted to a crank arm 27 secured to one end of drive shaft 28 journaled between the 50 base 1 and the cap 2, as clearly shown in Fig. 3. Attached to the opposite end of the drive shaft 28 is a sprocket wheel 29 or other driving element whereby the shaft 28 may be rotated from a prime mover. The shaft 55 28 carries a sprocket wheel 30 about which is trained a sprocket chain 31. This sprocket chain 31 extends forwardly and is adapted to actuate a mechanism (not shown) whereby the wire 24 is fed to the 60 cross head 16.

An upright shaft 32 is mounted in the cap 2, the upper end of the shaft 32 being curved as indicated at 33, the end 33 of the shaft 32 being engaged in the cap 2, so that the shaft 32 cannot rotate. Journaled upon 70 the shaft 32 and located in a recess in the cap 2 is a bending member 34. Comparing Figs. 6 and 7, it will be seen that the member 34 is provided with a transverse slot 35, the inner edges of which are indicated by 75 the reference characters 36 and 37. These edges 36 and 37 are not in alinement. The slot 35 in the bending member 34 is disposed opposite to a horizontally positioned, longitudinally extended slot 38 in the side 80 of the cap 2. Located in front of the slot 38 is an eye 39 through which the wire 34 passes before the wire enters the slot 38. The mouth of the slot 38 is closed by a cover plate 40 held in place by securing elements 41, the securing elements 41 being received in slots 41^a (see Fig. 10) formed transversely in the cover plate. The cover plate is thus permitted to have a vertical movement so that it may open and close the 90 slot 38. Projecting from the cover plate 40 are lugs 42 received in inclined notches 43 formed in an actuating bar 44, upheld for sliding movement by the securing elements 41 and received in a slot 45 formed in a lug 95 46 which outstands from the side of the cap 2. The lugs 42 and the notches 43 constitute interengaging elements coacting to move the cover plate or closure 40 to and from the slot or opening 38. A pin 47 (see Fig. 8) 100 extends across the slot 45 and guides the bar 44 in its reciprocating movement. The bending member 34 is provided with an upright pin 49 which is received in a notch 48 formed in the inner edge of the actuating bar 44. The pin 49 constitutes an eccentric element on the bending member 34, which element co-operates with the actuating bar 44. The bending member 34 extends into a pinion 50 and is held for rotation therewith 110 by a cap 51, the cap being secured in place by a tubular bolt 52 which enters the upper end of the bending member 34, as will be understood best from Fig. 3.

Let it be supposed that the wire 24, in a 115 straight length, has been moved by the cross head 16 in a rearward direction until the wire has passed through the slot 35 in the bending member 34 and into the slot 38 in the cap 2. If the bending member 34 be rotated through the medium of the pinion 50, the wire 34 will be bent as indicated at 53 in Figs. 7 and 13, around the shaft 32. When the bending member 34 is rotated, the 120 same through the medium of the pin 49 will 125 impart a sliding movement to the bar 44. The inclined notches 43 in the bar 44 engage the lugs 42 on the cover plate 40 and effect an elevation of the cover plate, so that the plate no longer extends across the slot 38. 130

Thus, when the wire 34 is bent as indicated at 53, the free end of the wire will be permitted to swing forwardly and out of the slot 38. After the wire has been bent, as indicated at 53, the bar 44 will be drawn rearwardly by the pin 49 and thus the cover plate 40 will be permitted to move downwardly, covering the slot 38, so that the cover plate will act as a guide for the rear, free curved end of the wire, when the wire is moved rearwardly. By the operation above described, the bend will be placed in the wire as indicated at 53. The bending member 34 rotates first in one direction and then in an opposite direction, and this motion is imparted to the bending member through the medium of a bar 54 which is supported for sliding movement on top of the cap 2. The bar 54 is provided with a rack 55 which meshes into the pinion 50, one end of the bar 54 being slidably received beneath a guide 56, attached to the cap 2, there being a screw 57 which enters the cap and is received in an elongated slot 58 in the bar 54, the slot 58 being shown most clearly in Fig. 2. One end of a link 59 is pivoted to the rack bar 54, the other end of the link 59 being pivoted to a crank disk 60 secured to a shaft 61 which is journaled in the cap 2. The shaft 61 carries a mutilated pinion 62 meshing into a mutilated pinion 63 secured to the drive shaft 28. From the foregoing it will be seen that a reciprocating movement will be imparted to the bending member 34 through a gear train comprising the rack bar 54-55, the link 59, the crank disk 60, the shaft 61, the pinion 62 and 63, the shaft 28 and the driving member or sprocket wheel 29. It has been stated hereinbefore that the end 33 of the shaft 32 is engaged in the cap 2. Owing to this fact, the shaft 32 is prevented from rotating, and when the bend 53 is formed around the shaft 32 by the action of the edge or shoulder 37, the wire will not be advanced when the bend 53 is made. This operation secures an even and equal length in the free ends which are formed by the bends indicated at 53. Journaled in the supporting structure is a shaft 89 terminally provided with a head 65, the end of which is provided with an outstanding shoulder 66, one end of which defines a cutting edge 67 adapted to cooperate with an anvil 68 held in the cap 2. The head 65 is equipped with a prong 69 which overhangs the shoulder 66. The end face of the head 65 and the adjacent edge of the prong 69, converge toward the cutting edge 67, as shown at 70. Attached to the prong 69 is an offset stop 71. Mounted for longitudinal sliding movement within the shaft 89 is a tubular ejector 64 and located within the ejector 64 is a supporting rod 72. The loop or bend 53 in the wire is advanced

across the shoulder 66 by the action of the cross head 16, and when the shaft 89 and the head 65 are rotated, the cutting edge 67 of the shoulder 66 will cooperate with the anvil 68 and cut off the wire at the point indicated at 74 in Fig. 14. The shoulder 66 will then move up around the supporting rod 72, the ends of the U-shaped piece of wire shown in Fig. 14 being formed into a pair of hooks as shown at 75 in Fig. 15. The arms of the U-shaped piece of wire indicated in Fig. 14 are engaged between the converging faces 70 of the prong 69 and the shoulder 66, and are brought into converging relation as shown at 73 in Fig. 16.

While the cutting and bending operation above referred to is taking place, the U-shaped section of wire is upheld by a support 76.

A block 77 is attached to the base 1 by means of screws 78, or is held thereon in any other desired manner. Through the block 77 passes the supporting rod 72 and the same is held in place by a set screw 79. The ejector 64 is mounted in a head 80 and is held therein by a set screw 81.

In order to impart a reciprocating movement of the ejector 64, a lever 82 is pivotally connected with the head 80, as indicated at 84, the lever being fulcrumed intermediate its ends as shown at 83, upon a projecting portion of the base 1. At its forward end, the lever 82 is equipped with a depending finger 85 which registers in a cam groove 86 formed in a disk 87 secured to the drive shaft 28.

Secured to the shaft 89 is a pinion 88 meshing into a rack 90 formed upon the lower rear portion of the bar 54.

Another tubular shaft 91 (see Fig. 7) and resembling the shaft 89, is journaled for rotation in the cap 2. The shaft 91 is equipped with a pinion 92 which meshes into the pinion 88. Secured to the shaft 91 is a head 93 provided with an outstanding shoulder 94, in which a pin 95 is slidably mounted, the pin 95 being constrained by a spring 96 to project beyond the shoulder. Located within the shaft 91 is a tubular ejector 97 by means of a set screw 98 in the head 80. A guide 99 is located within the ejector 97 and by means of a set screw 100, the guide 99 is held in the block 77. The guide 99 projects beyond the head 93 and is curved as indicated at 101. The bend 53 of the partially finished product shown in Fig. 15 is received by the shoulder 94 and is caught by the pin 95. When the head 93 is rotated, the pin will turn over the bend 53, across the guide 99, to form a hook indicated at 102.

A rotatory, oscillating motion is imparted to the head 65 by a gear train comprising the shaft 28, the pinion 63, the pinion 62, the shaft 61, the crank disk 60, the link 59, the

the rack 90 and the pinion 88. From the pinion 88 motion is transmitted to the pinion 92 and thence into the shaft 91 and the head 93. When the shaft 28 is rotated, the 5 disk 87 is rotated and the cam groove 86 through the medium of the finger 85 will tilt the lever 82, the lever 82 actuating the head 80 and the head 80 sliding the ejectors 84 and 97 on the guides 72 and 99 respectively. 10 The ejector 64 will push the hooks 75 off the end of the rod 72 and the ejector 97 will advance the hook 102 along the guide 99. The stop 71 serves to prevent the finished cross tie from swinging around too far in a horizontal direction when the hooks 75 are crowded by the ejector 64 off the end of the rod 72. The cross ties by the above operation will be deposited one by one in depending positions upon the guide 99 and as one 15 cross tie after another is deposited upon the guide, the cross ties will be moved along onto the curved end 101 of the guide, from which position they may be readily hooked onto the chains of links of the bed fabric. 20

25 It is desirable that the bend 53 be not made in the wire until the advanced portion of the wire be cut off as indicated at 74. In order to accomplish this result, the edge 37 of the bending member is located out of 30 alinement with the edge 36 (see Fig. 7) and consequently, the cut indicated at 74 will be made by the edge 67 of the shoulder 66 and the anvil 68 before the bend 53 is made by the edge 37 and the shaft 32, as shown in 35 Fig. 7.

In Figs. 11, 12 and 18 a modified form of the invention is shown, the modification consisting in equipping the guide 99 with a head 106 comprising a body 103, and a 40 curved end 104, the body and the end 104 having a slot 105 across which extends a cap 107. The body 103 is inclined transversely and the end 104 lies at an angle thereto. The hook 102—53 rides into the 45 slot 105 and the tie is advanced along the head. Owing to the fact that the body is transversely inclined as clearly shown in Fig. 18, that end of the tie which carried the hooks 75 is depressed as the tie moves 50 along the head. As a consequence, when the tie is advanced along the head, that end of the tie which carries the hooks 75 is permitted to pass under one chain of links in the fabric. The hook 102—53 as it traverses 55 the end 104, is engaged with this chain and the hooks 75 are engaged with another parallel chain, it being noted that after the tie passes off the transversely inclined body 103 and traverses the end 104, the tie is moved 60 to a position parallel to the plane defined by the two chains above referred to.

Especial attention is directed to the curved form of the crank 27. The form of the crank is important, since, owing to its curved 65 shape, the free end of the wire, when the

bend 53 is made, is permitted to swing through the crank.

Obviously by loosening the bolt 52, the pinion 50 may be rotated upon the bending member 34. In this manner, the edge 37 70 may be adjusted, so as to exercise its function as hereinbefore set forth.

The operation of the structure has been dealt with hereinbefore step-by-step, but generally considered, is as follows:—The 75 shaft 28 through the medium of the crank 27 and the link 26 causes a reciprocation of the cross head 16, the trip 6 causing the grip 20 to engage the wire 24 and slide the same. The bend indicated at 53 is formed 80 around the shaft 32 by the edge 37 of the bending member 34, the bending member 34 being rotated by means of the rack 55 on the bar 54, the bar 54 being actuated by the link 59, the cam disk 60, the shaft 61, the pinion 62, the pinion 63 and the shaft 28. The cut indicated at 74 in the finished product and the bend indicated at 75 are formed by the shoulder 66, the head 65 and the shaft 89 being rotated through the medium of the pinion 88 and the rack 90 on the rack bar 54. The bend indicated at 102 in the finished product is secured by the shoulder 94, the head 93 being rotated by the shaft 91, which in its turn is rotated by the intermeshing 95 pinions 89 and 92. The ejectors 97 and 64 are operated from the head 80 by means of the lever 82, the lever being actuated from the shaft 28 by the disk 87 and its groove 86. Owing to the fact that the mutilated pinion 90 100 meshes into pinion 62 for a portion only of the time during which the shaft 28 is rotating, there will be a pause between each complete forward and backward stroke of the rack bar 54, and consequently between 105 each movement of the heads 65, and 93, such movement comprising a rotation first in one direction and then in the other. Owing to the fact that the mutilated pinion 63 does not mesh continuously into the pinion 62, the reciprocating movement of the cross head 16 and consequently the advance of the wire 24 will be properly timed with respect 110 to the cutting and bending operations.

Having thus described the invention, what 115 is claimed is:—

1. In a device of the class described, means for advancing the material and for severing a section therefrom; means for forming hooks at the ends of the section; 120 a guide adapted to receive one hook; and means moving in a right line and exerting a continuous pressure throughout its stroke, for advancing the section transversely to cause the hook to traverse the guide.

2. In a device of the class described, a 125 slidably mounted cross head; a material engaging grip movably mounted upon the cross head; a member coöoperating with the grip when the cross head is reciprocated, to 130

cause the grip to engage the material; a movable member coöperating with said other member to render the same inoperative to actuate the grip; means for severing a section from the material; and means for shaping the section.

3. In a device of the class described, a slidably mounted cross head; a movable member upon the cross head and adapted to bind the material upon the cross head; a pivotally mounted trip; a projection upon the movable member adapted to engage the trip; a movable guide adapted to prevent the projection from engaging the trip; means for cutting a section from the material; and means for shaping the section.

4. In a device of the class described, a movably mounted cross head; a grip fulcrumed intermediate its ends upon the cross head and adapted to coöperate with the cross head in engaging the material; a movably mounted trip adapted to engage one end of the grip, to tilt the grip and to bring the other end of the grip into engagement with the material; a guide movable into coincidence with the trip and constituting means for preventing the grip from engaging the trip; means for severing a section from the material; and means for shaping the section.

5. In a device of the class described, a movably mounted cross head provided with spaced guiding means; a grip upon the cross head operating between the guiding means; mechanism for operating the grip when the cross head is reciprocated; means for severing a section from the material which is advanced by the cross head; and mechanism for shaping the section.

6. In a device of the class described, a rotary bending member having a slot defining a shoulder; a shaft upon which the bending member is journaled; means for introducing the material between the shaft and the shoulder; means for rotating the bending member to cause the shoulder to coöperate with the shaft in forming a loop in the material; means for severing the loop; and mechanism for shaping a hook in the loop.

7. In a device of the class described, a supporting structure having an opening; a rotary bending member having a slot aligned with the opening; a closure for the opening; and means operatively connecting the closure with the bending member to move the closure to and from the opening.

8. In a device of the class described, a supporting structure having an opening; a rotary bending member; a closure for the opening; a slidably mounted actuating member, the actuating member and the closure being provided with interengaging elements coacting to move the closure to and from the opening; and an eccentric element on the bending member coöperating with the actuating member.

9. In a device of the class described, a relatively fixed support; and a member rotatable upon the support, the member having a shoulder having a bending face coacting with the support to bend the material into a hook and provided with a cutting edge; and a relatively fixed anvil coöperating with the cutting edge of the shoulder to effect a severing of the material prior to the formation of the hook.

10. In a link making machine, a link support; a bending member rotatable with the support as an axis; an ejector slidable in the bending member longitudinally of the support and transversely of the bending member; means for rotating the bending member; and means for reciprocating the ejector in the bending member.

11. In a device of the class described, fixed supports and bending members having projections movable around the supports to effect a simultaneous bending of both ends of the material, one of the projections only being provided with cutting means; and a relatively fixed cutting means coöperating with the first specified cutting means only, and independent of the other projection.

12. In a device of the class described, supports; rotary bending members having projections coöperating with the supports to effect a bending of both ends of the material; and ejectors slidable upon the supports to force the material along the supports.

13. In a device of the class described, supports; bending members having projections movable around the supports and adapted to form hooks in the material; ejectors movable upon the supports; and a stop carried by one bending member and located beyond the end of said bending member.

14. In a device of the class described, a supporting structure; a drive shaft journaled therein; a second shaft journaled on the supporting structure; pinions upon the shafts, one of said pinions being a mutilated pinion, a slidably mounted rack-bar; means for connecting the rack-bar operatively with the second shaft; and a bending member having a pinion meshing into the rack-bar.

15. In a device of the class described, a supporting structure; a cross-head slidable thereon and provided with means for engaging the material; a drive shaft journaled in the supporting structure; a crank arm on the drive shaft; a link connecting the crank arm with the cross-head; a second shaft journaled for rotation in the supporting structure; intermeshing pinions upon the shafts, one of said pinions being a mutilated pinion; a rotatably mounted bending member; and means for operatively connecting the bending member with the pinion of the second shaft.

16. In a device of the class described, a support; a bending member coöperating with the support; and an ejector slidable upon the support; a supporting structure; a lever fulcrumed thereon and operatively connected to the ejector; a drive shaft journaled in the supporting structure and provided with a cam wheel, the lever having means for engaging the cam wheel.
17. In a device of the class described, a guide comprising a body and an angularly disposed end; and means for moving bed-forming members along the body and upon the end, the body and the end being placed in angularly disposed planes to effect a tilting of the bed-forming members at one end, as the bed-forming members traverse the guide.
18. In a device of the class described, a guide, means for fashioning a bed-forming element and for depositing the same upon the guide; and an ejector coöperating with the guide to force the bed-forming element free from the guide for engagement with the chain of a bed structure.
19. In a device of the class described, a slidably mounted cross-head; a material-engaging grip movably mounted upon the cross-head; a member coöperating with the grip when the cross-head is reciprocated, to cause the grip to engage the material; a movable member coöperating with said other member to render the same inoperative to actuate the grip; and means for severing a section from the material.
20. In a device of the class described, a slidably mounted cross-head; a material-engaging grip movably mounted upon the cross-head; a member coöperating with the grip when the cross-head is reciprocated, to cause the grip to engage the material; a movable member coöperating with said other member to render the same inoperative to actuate the grip; and means for shaping the material.
21. In a device of the class described, a slidably mounted cross-head; a movable member upon the cross-head and adapted to bind the material upon the cross-head; a pivotally mounted trip; a projection upon the movable member adapted to engage the trip; a movable guide adapted to prevent the projection from engaging the trip; and means for shaping the material.
22. In a device of the class described, a slidably mounted cross-head; a movable member upon the cross-head and adapted to bind the material upon the cross-head; a pivotally mounted trip; a projection upon the movable member and adapted to engage the trip; a movable guide adapted to prevent the projection from engaging the trip; and means for cutting a section from the material.
23. In a device of the class described, a movably mounted cross-head; a grip fulcrumed intermediate its ends upon the cross-head and adapted to coöperate with the cross-head in engaging the material; a movably mounted trip adapted to engage one end of the grip, to tilt the grip and to bring the other end of the grip into engagement with the material; a guide movable into coincidence with the trip and constituting the means for preventing the grip from engaging the trip; and means for operating upon the material.
24. In a device of the class described, a movably mounted cross-head provided with spaced guiding means; a grip upon the cross-head, operating between the guiding means; means for operating the grip when the cross head is reciprocated; and means for operating upon the material.
25. In a device of the class described, a rotary bending member having a shoulder; a shaft upon which the bending member is journaled; means for introducing the material between the shaft and the shoulder; means for rotating the bending member to cause the shoulder to coöperate with the shaft in forming a loop in the material; means for severing the loop; and mechanism for shaping a hook in the loop.
26. In a device of the class described, supports; bending members having projections movable around the supports and adapted to form hooks in the material; ejectors movable upon the supports; and a material-engaging stop located adjacent the end of one bending member.
27. A wire-bending machine of the type described, including rotary bending devices, wire-supporting means intermediate said bending devices, means for actuating said bending devices, one bending device being equipped with a cutting member, and a shaft carrying a head equipped with a prong, said head and said prong having opposite converging edges.
28. A wire-bending machine of the type described, including rotary bending devices, wire-supporting means intermediate said bending devices, means for actuating said bending devices, one bending device being equipped with a cutting member, and a shaft carrying a head equipped with a prong, said prong being equipped with an offset stop, said head and said prong having opposite converging edges.
29. A wire-bending machine of the type described, including rotary bending devices, wire-supporting means intermediate said bending devices, means for actuating said bending devices, a shaft carrying a head equipped with a prong, said head and said prong having opposite converging edges, one bending device having a cutting member, the

other bending device having a slidable resiliently seated pin, said prong also having an offset stop.

30. A wire bending machine of the type described, including rotary bending devices, one bending device having a shoulder, one end of which shoulder is provided with a cutting member, the other bending member having a slidable resiliently seated pin, actuating means for said bending devices, wire-supporting means intermediate said bending devices, and a shaft equipped with a head provided with a prong, said prong having an offset stop, said head and said prong having opposite converging edges.

31. A wire-bending machine of the type described, including a driving shaft, a second shaft, said shafts being intergeared, the gearing of said shafts having intermittent rotary action, a slidable rack, means operatively connecting said rack with said sec-

ond shaft, and a bending device geared to said rack.

32. In a device of the class described, a supporting structure; a bending member 25 operating therein, the bending member being adapted to engage the material and to swing the free end thereof; and means for actuating the bending member, said means including a crank arm located adjacent the 30 bending member, the arm being of loop form to permit the free end of the material to pass through the crank when the free end is swung by the bending member.

In testimony that I claim the foregoing as 35 my own, I have hereto affixed my signature in the presence of two witnesses.

GARY B. SMITH.

Witnesses:

SELINA WILLSON,
I. E. SIMPSON.
